UNITED STATES PATENT OFFICE.

MINARD A. POSSONS, OF CLEVELAND, OHIO, ASSIGNOR TO AMERICAN STOVE COMPANY,
OF ST. LOUIS, MISSOURI, A CORPORATION OF NEW JERSEY.

PROPORTIONAL GAS AND AIR MIXER.

1,191,823.

Specification of Letters Patent Patented July 18, 1916.

Application filed January 3, 1916. Serial No. 70,001.

To all whom it may concern:

Be it known that I, MINARD A. POSSONS, a citizen of the United States, residing at Cleveland, in the county of Cuyahoga and State of Ohio, have invented certain new and useful Improvements in Proportional Gas and Air Mixers, of which the following is a specification, reference being had thereto to the accompanying drawing.

10 This invention relates to improvements in proportional gas and air mixers, the primary object of which is to have the shutter operatively connected with the gas valve whereby the amount of air fed to the gas supply is automatically regulated in proportion to the supply of gas through the gas valve.

A further object of my present invention is to operatively connect the shutter with an 20 adjustable gas orifice which controls the amount of gas fed to the burner, thereby automatically proportioning the proper amount of air and gas which are supplied to the burner.

25 A further object of my present invention is to operatively connect a gas valve with an adjustable gas orifice and to operatively connect the shutter with the said valve and adjustable orifice, whereby the proportion of 30 gas and air are automatically regulated as the supply of gas is increased or diminished.

A further object of my present invention is to operatively connect an automatic air control and a gas valve for automatically 35 proportioning the amount of gas and air, and to combine with these an adjustable air controlling shutter to adapt the device for different kinds of gas and for different grades of gas.

40 A further object of my invention relates to the specific arrangement and construction of parts whereby the proper proportion of air and gas supplied to the burner is automatically controlled.

45 In the accompanying drawings, Figure 1 is a front elevation of a gas burner shutter and gas valve which embody my invention. Fig. 2 is a sectional view showing the shutter and gas supply wide open. Fig. 3 is an 50 inverted plan view showing the operative parts in position with the gas supply closed. Fig. 4 is an interior plan view partly in section showing the adjustable shutter

moved to limit the amount of air in the proportion to the amount of gas supplied. Fig. 5 is an interior view of the shutter with the gas orifice and gas valve removed and the shutter shown wide open. Fig. 6 is a perspective view of the parts comprising the improvement in separated relation. Fig. 7 is a sectional view showing the gas supply closed. Fig. 8 is an interior elevation showing the gas supply closed.

It is well understood by those skilled in this art that gas burners operate on the Bunsen principle, in that there is a mixture of air and gas that are supplied to the burner head from which it flows and is ignited. It is also understood by those skilled in this art that in order to get proper combustion, it is essential to obtain a proper proportion of air and gas. For this purpose in gas stoves there is supplied what is known as a "shutter," for adjustably controlling the amount of air that is supplied to the gas conduit to be mixed with the gas that is fed to the burner.

In carrying out my invention, I provide a stationary shutter casing 1 which has a hub portion 2 connected with the valve casing 3 in which the ordinary gas valve or cock 4 is located and turns in the usual manner. The outer shutter casing 1 as here shown, is attached to the valve casing 3 by screw-threads, though other means of connection may be provided without affecting my present improvement. For the purpose of operating the gas valve 4, it is provided with the usual laterally extending handle 5, and the valve and casing are provided with the usual gas ports 6 and 7, and these gas ports are caused to register and not to register by the turning of the gas valve in the usual way. The shutter casing 1 is provided with a plurality of air inlet openings 8 through which air will pass into the mixing tube 9 (Fig. 7) and into which tube the gas also passes through a gas orifice 10.

Thus far, I have described a gas valve and a shutter which does not materially differ from that in common use.

Referring now particularly to my improvement, I provide an adjustable orifice member 11 that is located and longitudinally movable within the projecting end 12 of the valve casing 3. The gas port 7 of the

valve casing 3 has projecting inwardly therefrom a hollow projection 13 with its end terminating with a needle valve 14. This member 13 projects within the longitudinally movable nozzle 11, and its needle valve 14 is adapted to enter and coöperate with the gas orifice 10 for controlling the flow of gas through the said orifice. A plurality of gas outlet passages 15 are formed in the end of the hollow projection 13 so that gas may flow from the port 7 through these passages into the nozzle 11 and through the orifice 10 when the orifice is not closed by the needle valve 14 and the gas valve 4 is in its open position. If desired, a packing 16 may be provided between the nozzle 11 and the adjacent inner wall of the valve casing 3 to prevent any leakage of gas between these parts.

20 A movable shutter 17 coöperates with the stationary shutter casing 1 to control the flow of air through the shutter, and this movable shutter member 17 is operatively connected with the gas valve 4 in the following manner: A sleeve 18 loosely surrounds the projecting end 12 of the valve casing 3, and this sleeve has its outer edge provided with a projection 19 that fits in an opening 20 of the movable shutter 17. In 25 the construction here shown, the movable shutter 17 is placed within the stationary shutter casing 1 and is provided with a plurality of air passages 21 corresponding in number, shape and approximately in size 30 with the air openings 8 of the casing 1. This projection 19 extends through an elongated opening 22 formed in the stationary casing 1 thus permitting the oscillation of the sleeve 18 and as it is oscillated, the movable shutter 17 will be correspondingly oscillated.

35 The gas valve 4 is operatively connected with the sleeve 18 by providing a segmental gear 23 that is carried by one end of the gas valve, and as here shown, it is carried by the 40 end opposite the handle 5, and the segmental gear is provided with an angular opening 24 fitting an angular projection of the end of the gas valve 4, and the segmental gear is held in position by the usual spiral spring 45 26, washers 27 and screw nut 28. Meshing with the segmental gear 23 are gear teeth 29 formed on the adjacent edge of the sleeve 18. From the foregoing, it will be understood that when the gas valve is turned, the 50 sleeve and the movable shutter 17 are correspondingly turned. In this way when the gas valve is open the shutter 17 moves and will close the air openings 8 of the stationary casing 1 according to the amount of gas 55 passing through the gas port.

60 The gas valve 4 has a quarter turn from open to closed positions, and by reason of this amount of movement, with the gear ratio here shown the movable shutter 21 is 65 moved a distance twice that of the size of

the air openings 8 since the air openings are of a width approximately one-eighth of the circumference of the shutter casing 1. Owing to this fact with the gas valve in closed position (as shown in Fig. 7) the air passages 8 and 21 register so that they are full open. However, owing to the size of the gas ports 6 and 7 it requires approximately one half of the movement of the gas valve before the ports 6 and 7 begin to register, and this movement half is equivalent to one-eighth of a complete circle of movement so that when the gas valve has moved half of its path the passages 8 and 21 are out of register and the air openings of the shutter 80 closed. A further opening movement of the valve will admit gas and immediately the air passages of the shutter begin to open and the opening increases as the valve is open, and when full open, the air passages are correspondingly full open.

85 Thus far, I have described one feature of my invention, viz., operatively connecting a movable shutter with the gas valve so that as the gas is supplied, the amount of air is 90 automatically supplied in proportion to the flow of gas.

95 It is known to those skilled in the art that different grades of gas, and different kinds of gas require different amounts of air for proper combustion. This is particularly true in respect to natural and artificial gas, and to a certain extent is true in respect to different grades of the same kind of gas. In 100 order to adopt my automatic shutter to universal use for different kinds and grades of gas, I provide means for limiting the size of the air passages of the shutter according to the conditions of the local markets. This I 105 accomplish by means of an adjustable shutter 30 which is of a cup-shaped form and will fit within the cup-shaped stationary casing 1. This adjustable cup-shaped shutter 30 is provided with air passages 31 which correspond in number, size, and shape to the 110 passages 8 and 21 of the shutter members 1 and 17, the center portion of the shutter 30 being cut out as shown at 32 for the accommodation of certain other constructions to be described presently, and because it is not 115 necessary that the wing 33 of the shutter 30 extend over the hub portion 34 of the casing 1.

120 The adjustable shutter member 30 is made of a size to snugly fit within the shutter casing 1 and its annular wall is provided with knocked out lugs 35 adapted to spring outward into the slots 36 of the annular wall of the casing 1 and to engage the underside of the outer wall of the openings 36 thus removably holding the adjustable shutter 30 in position within the casing 1. From this, 125 it will be understood that the shutter 30 may be turned within the casing 1 to carry its wings extending over the air openings of the 130

two members 1 and 17 for the purpose of limiting the size of those openings as shown in Fig. 4, according to the demands of the particular kind or grade of gas being used 5 in any particular locality.

From the foregoing, it will be understood that I have combined an adjustable shutter with the movable shutter that is operatively connected with the gas valve for the purpose 10 of automatically controlling the flow of air according to the flow of gas, and to further provide means for adjusting the size of the air openings of the movable and stationary parts of the burner for the purpose of 15 accommodating it to local gas conditions.

Thus far I have described my invention of the automatic and adjustable shutter for use with the ordinary gas valve 4. However, owing to the gas ports 6 and 7 of the ordinary 20 gas valve and the gas valve casing, the adjustment of the gas supply is not well adapted for a fine adjustment.

For the purpose of providing means which adapt the gradual increase of gas supply as 25 the gas valve and shutter are open thereby providing a gradual supply of gas and a corresponding gradual supply of air proportioned to each other, I provide and combine with the automatic and adjustable shutters, 30 an automatically adjustable gas supply orifice. The automatically adjustable supply orifice of my present invention is combined with the aforesaid features in the following manner: I have previously referred herein 35 to the nozzle 11 and the needle valve 14 for controlling the orifice 10 of the nozzle 11, and I will now explain how the supply of gas is gradually controlled through the orifice 10 in proportion to the gradual opening 40 of the air passages of the shutter members. I accomplish this by providing the nozzle 11 with a lateral pin or pins 37 which project into cam shaped passages 38 of a hub 39 which projects from the movable shutter 17, so that as the shutter 17 is turned back and forth, the walls of the cam passages move the nozzle 11 in and out in respect to the needle 14, and in that way gradually opens and closes the orifice 10 and 45 gradually increases and diminishes the supply of gas as the shutter 17 is gradually moved for opening or closing the air passages of the shutter members. Any suitable means may be provided for preventing the 50 rotation of the nozzle 11, but as here shown, it consists in providing the inner end of the nozzle 11 with a slot 40 which receives a pin 41 projecting inward from the portion 55 of the valve casing.

As herein stated, the valve 4 is moved throughout one eighth of a circle before the ports 6 and 7 begin to register for the flow of gas, and because of this the orifice 10 must not begin to open until the ports 6 and 7 begin to register. This is accomplished

by providing the cam slot 38 with the straight portion 42 of a length to permit the valve 4 to be turned sufficiently for the ports 6 and 7 to begin to register before the nozzle 11 begins to move out for opening 70 the orifice 10. As soon as the ports 6 and 7 begin to register, the nozzle 11 begins to move outwardly and the orifice 10 is gradually opened, thus providing a gas supply control capable of gradual and uniform 75 control which is not so true of the ports 6 and 7 of a gas valve and gas casing. By reason of the use of this adjustable nozzle, I am enabled to more accurately proportion the amount of gas supply with the amount 80 of air supply. For the purpose of permitting a small supply of air through the shutter at all times, I provide one wall of the openings 8 formed in the member 1 with notches 43. By this means there is always 85 permitted a small supply of air to the mixing chamber so that there will be air for any gas that may find its way into the mixing chamber as the valve and orifice are being open, should they open slightly before 90 the movable shutter member 17 has opened the air passages 8 of the casing 1, and to supply a sufficient quantity of air when the burner is turned down low and the shutter approximately closed. For the purpose of 95 facilitating the assembling and separating of the parts, notches 44 in communication with the cam slots 38 are provided to permit the entrance and removal of the pins 37 into the cam slots.

Having thus fully described my invention what I claim and desire to secure by Letters Patent is:

1. In a gas control for gas stoves, the combination of a valve casing having a gas port terminating in an outlet orifice, a main valve controlling the gas port in advance of the orifice, an adjustable member controlling the orifice, and an operative connection between the valve and the adjustable member, 105 the operative connection including a slot having an initial straight wall extending in the direction of movement of the connection and a final cam-wall to permit the opening of the main valve in advance of the operation of the adjustable member.

2. In a gas control for gas stoves, the combination of a valve casing having a gas port terminating in an outlet orifice, a main valve controlling the gas port in advance of the 110 orifice, an endwise adjustable member controlling the orifice, an oscillating member operatively connected with the main valve, having a slot and pin connection with the endwise adjustable member, the slot having 115 a straight wall and a cam-wall and an operative connection between the main valve and oscillating member for the purpose described.

3. A shutter for gas stoves comprising a 120

- valve casing and a valve therefor, the valve casing having a projection, an oscillating gear member carried by the casing projection, a stationary shutter member and a movable shutter member, both having air openings for the purpose described, the oscillating gear member connected with the movable shutter member, and a gear operated by the gas valve and meshing with the oscillating gear member.
4. A shutter for gas stoves comprising a valve casing having a projection and a valve for the casing, an oscillating sleeve carried by the said projection, stationary and movable shutter members having air openings, the sleeve having a projection engaging the movable shutter member and a gear connection between the sleeve and the valve for the purpose described.
20. 5. A shutter for gas stoves comprising a gas valve casing and a valve therefor, the valve and casing having gas ports, an adjustable orifice member for controlling the gas supply, movable and stationary shutter members for controlling the air supply, an operative connection between the gas valve and the shutter member, and a cam connection between the adjustable orifice member and the shutter, the connection hav-
- ing a straight way and an inclined way for 30 the purpose described.
6. A gas and air control for gas burners, comprising a valve casing having a gas port terminating in a gas orifice, a main gas valve controlling the gas port, an adjustable member for the orifice, stationary and oscillating shutter members for controlling the air supply, the oscillating shutter member having a hub surrounding the orifice, adjustable member, the said hub and adjustable member having a cam and slot connection for 40 moving the adjustable member, and an operative connection between the oscillating shutter member and the main gas valve.
7. A gas and air control for gas burners, comprising a valve casing having a gas port, a main gas valve controlling the gas port, stationary and movable shutter members for controlling the air supply, an oscillating member having a projection extending 45 through the stationary shutter member and engaging the movable shutter member for operating it, and an operative connection between the main gas valve and the oscillating member.
- 55 In testimony whereof I hereunto affix my signature.

MINARD A. POSSONS.
